UNITED STATES PATENT OFFICE.

CARL J. JACOBSEN, OF DE PERE, WISCONSIN.

CHILD'S CART.

1,155,928.

Specification of Letters Patent.

Patented Oct. 5, 1915.

Application filed January 2, 1915. Serial No. 250.

To all whom it may concern:

Be it known that I, CARL J. JACOBSEN, a citizen of the United States, residing at De Pere, in the county of Brown and State 5 of Wisconsin, have invented a new and useful Child's Cart, of which the following is a specification.

The present invention appertains to a child's cart or carriage, and aims to provide a vehicle of that character embodying 10 novel means for accommodating a child or children at different seated positions thereon.

It is the object of this invention to provide a structure of the character indicated, the body or frame of which carries a pair 15 of seats, each having a back and foot rest associated therewith, and the parts being so mounted as to permit of their reversal, in order that the children may sit face to face, 20 back to back, or facing in the same direction looking either forwardly or rearwardly.

Among its specific objects, the invention aims to provide novel reversible seats for 25 the cart body or frame; novel means whereby the back of each seat may be reversed and held at different positions with respect to the seat; and novel reversible foot rests for the seats to coöperate properly there- 30 with at the various positions of the seats.

It is also within the scope of the invention, to provide a structure of the nature specified, which will be comparatively simple and inexpensive in construction, as well 35 as being convenient, practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 45 within the scope of what is claimed without departing from the spirit of the invention.

The invention is illustrated in its preferred embodiment in the accompanying drawings, wherein:

Figure 1 is a side elevation of the improved child's cart, portions being broken away. Fig. 2 is a plan view of the cart, portions being broken away. Fig. 3 is a cross section of the cart, taken on the line 55 3-3 of Fig. 1. Fig. 4 is a sectional detail

taken on the line 4-4 of Fig. 1. Fig. 5 is an enlarged fragmental perspective view illustrating one of the latches coöperable with the back supporting means.

In carrying out the invention there is provided a sulky cart, embodying a two-part axle 1 having suitable ground or supporting wheels 2 journaled upon the end portions or spindles thereof, and a rectangular frame 3 is mounted or secured upon the axle 1 between the wheels 2.

A pair of angular or L-shaped hounds 4 have their adjacent ends secured to the tongue or handle 5, and have their remote ends disposed above the axle 1, and secured upon brackets 6 which in turn are secured upon the side portions of the frame 3. The brackets 6 are arranged in pairs at the opposite sides, and are U-shaped, with their 75 bends secured together, and with their arms spaced vertically and secured to the hounds 4 and frame 3. The tongue or handle 5 is provided with a depending portion 7, to the lower or free end of which is pivoted a 80 U-shaped leg 8 which may be swung downwardly to support the body or frame of the cart against tilting. The leg 8 may normally be swung upward against the portion 7 of the tongue or handle 5, to be out 85 of the way. Fenders 9 are preferably mounted above the wheels 2 by means of brackets 10 carried by the axle 1.

The body of the cart embodies rectangular or elongated side frames 11 having the 90 fillers, 12, and transverse rods 13 secured to the lower longitudinal bars of the side frames 11 between the axle 1 and ends of the body or side frames 11 thereof. The end portions of the rods 13 project outwardly beyond the side frames 11 of the body, and form pintles which are embraced by the ends of semi-elliptical leaf springs 14 secured upon the frame 3, whereby the cart body is yieldably supported upon the axle 100 frame 3, for the comfort of the occupant or occupants.

A pair of seats 15 is carried by the rods 13, each of the seats 15 being mounted for rotation upon one of the cross bars 13, and that portion of each seat which is fulcrumed or pivotally mounted upon the respective rods 13, is arranged adjacent one edge portion of the seats. Thus, the seats 15 may be swung toward the ends of the body so as to 105 project away from each other, as seen in full lines in Fig. 1, to provide an opening 110

2
between the two seats, or the seats may be swung inwardly toward and adjacent each other as suggested in dotted lines in Fig. 1. The lower longitudinal bars of the side frames 11 are provided with suitable inwardly projecting stops 16 for supporting the seats 15 at either position thereof.

Each seat is equipped with a suitable back 17 which is arranged to be reversed and held at different positions. Thus, a pair of links 18 is pivoted to the side edges of each back 17, intermediate the upper and lower edges of the back, and the links 18 are also pivoted to the free ends of a pair of arms 19 fulcrumed upon the corresponding rod 13, between the side edges of the respective seats 15 and the side frames 11. The arms 19 are mounted for rocking or oscillatory motion upon the rods 13, and the upper and lower edges of the backs 17 and those edges of the seats 15 remote from the rods 13, are provided with suitable interengagable portions to hold them together.

In order to hold the arms 19 upright or vertical, to hold the backs 17 in a like position, sleeves 20 are secured upon the lower longitudinal bars of the side frames 11 adjacent the ends of the rods 13 and are provided with upwardly projecting standards 21 carrying latches 22. Each of the latches 22 embodies a U-shaped handle 23 straddling and terminally pivoted to the respective standard 21, and the terminals of the handle 23 are provided with angularly extending fingers 24 which project inwardly, and which are arranged to straddle or engage the respective arm 19 when the handle 23 is swung upwardly at the outer side of the standard 21. Thus, when the arms 19 are swung to upright position, the latches 23 may be swung to engage and hold the arms 19 upright, whereas if the latches 23 are released from the arms 19, the arms 19 may swing into alignment or straight line position with the links 18, so that the backs 17 may swing to inclined positions, as suggested at the left hand end of Fig. 1.

Coming to the foot rests, the same are carried by rigid hangers 25 depending from the sleeves 20, the lower ends of the hangers 25 at the opposite sides being connected by longitudinal stays or rods 26 which are provided with downwardly curved portions 27 at those ends of the rods 26 remote from the tongue or handle 5. The portions 27 are designed to strike the sidewalk or underlying surface for preventing the excessive tilting of the cart in the corresponding direction.

60 A foot rest 28 is provided for each seat 15, the same being of angular construction, and having a pair of tread portions arranged at an obtuse angle relative to one another. Thus, each foot rest comprises a 65 pair of angular side members 29, the arms

of which are arranged at an obtuse angle relative to one another, and cross members 30 connecting the terminals of the side members 29, there being a meshed wire or other filler 31 between the members 29 and 30 of the foot rest frame, to provide suitable tread portions which are yieldable, and which permit the dirt to pass therethrough readily. As will be evident, the two tread portions of the fabric or wire mesh filler 31 are arranged at an obtuse angle relative to one another. Webs 32 are secured between the arms of the side member 29 of the foot rest adjacent the elbow thereof, and are pivotally engaged with the lower ends of the corresponding pair of hangers 25, as at 33, whereby the foot rest may be oscillated or swung to reversed positions. Consequently, when onehalf or portion of the foot rest is swung upwardly against the respective seat and the side frames 11 of the body, the other half or tread portion of the foot rest will be disposed horizontally and in a lowered position, as clearly obvious by reference to Fig. 1, to receive thereon, the feet of the person occupying the corresponding seat. The foot rests are reversible, so that they may be reversed when the seats are reversed.

The present cart is adapted particularly for carrying children, and is adjustable to accommodate the children seated face to face, or back to back, or facing the same direction looking toward the person with the handle of the cart, or facing in the same direction looking away from the person who is at the handle.

When it is desired that the children sit facing each other, the seats 15 are swung away from each other toward the ends of the cart body, as illustrated in full lines in Fig. 1, and the backs 17 are moved properly to the ends of the cart to engage and rest upon the remote edges of the seats 15. The foot rests are also swung to the full line position illustrated in Fig. 1, whereby the lower horizontal tread portions of the foot rests will meet to provide a continuous foot rest for receiving the feet of the occupants thereon, it being noted that the seats 15 are spaced apart to provide an opening therebetween for accommodating the children's legs. The upwardly projecting portions of the foot rests in bearing against the seats 15 and frames 11 will prevent the lower portions of the foot rests from being depressed by the weight imposed thereon. When the seats, back and foot rests are thus positioned, as seen in full lines in Fig. 1, the children may sit facing each other.

To enable the children to sit back to back, the seats 15 are swung inwardly, the backs 17 are inverted and moved inwardly adjacent each other, and the foot rests are reversed, so that the parts assume the dotted

line positions seen in Fig. 1, and in which event the children may sit upon the seats back to back. The backs and foot rests of the seats will accommodate the children at each position of the parts, the back and foot rest of each seat serving their offices in the same manner at either position of the parts.

Since each seat, back and foot rest may be adjusted independently of its mate, it will be observed that the seats, backs and foot rests may be adjusted so that the children may sit looking in the same direction, either facing the person at the handle, or looking in the opposite direction.

15 Each back 17 may either be held upright, or in an inclined position, at either position of the seat. To hold the backs 17 upright, the arms 19 are swung upright and engaged by the latches 23, so that each back will be held upright, as seen at the right hand end of Fig. 1, whereas if the arms 19 are released, the backs will be held in an inclined position as seen at the left hand end of Fig. 1. When the backs are supported in an up-right position, it will permit the children to sit upright in a convenient manner, whereas if the backs are tilted or inclined, this will permit the reclining posture of the children.

20 30 The parts may be readily adjusted in a moment's time, and the construction of the device is such, as to render it comparatively simple, practical and efficient.

Having thus described the invention, what is claimed as new is:—

1. In a device of the character described, a frame, a pair of seats movably carried by the frame and arranged to be disposed adjacent or spaced from each other, a back for each seat, and means for supporting the backs at the adjacent edges of the seats when the seats are arranged adjacent each other, and for supporting the backs at the remote edges of the seats when the seats are spaced apart.

2. In a device of the character described, a frame, a pair of seats movably carried thereby and adapted to be moved adjacent one another or spaced apart, a back for each seat, and links connecting the backs and frame whereby the backs may be reversed to coöperate properly with the seats at either position thereof.

3. In a device of the character described, a frame, a pair of seats each pivotally connected to the frame adjacent one edge portion whereby the seats may be swung to project toward or away from each other, a back for each seat, and means for supporting each back at that edge portion of the respective seat remote from the pivotal point of the seat, at either position of the seat.

4. In a device of the character described, a frame, a pair of seats each pivotally engaged with the frame adjacent one edge por-

tion whereby the seats may be swung to project toward or away from each other, a back for each seat and coöperable with that edge portion of the seat remote from the pivotal point thereof, and links connecting the backs and frame whereby the backs may be reversed when the seats are reversed.

5. In a device of the character described, a frame comprising side members and a pair of cross members connecting them, a seat pivotally engaged adjacent one edge with each cross member and adapted to be supported by the side members, the seats being arranged to be swung so as to project in either direction, a reversible back for each seat coöperable with that edge thereof remote from the respective cross members, and links connecting the backs and cross members to support the backs at either position thereof.

6. In a device of the character described, a frame, a pair of seats movably supported by the frame and arranged to be moved adjacent each other or spaced from each other, and a pair of foot rests carried by the frame and arranged to be reversed for proper co-operation with the seats at the different positions thereof, the foot rests being arranged to meet each other when the foot rests are adjusted to accommodate the seats when spaced apart.

7. In a device of the character described, a frame, a pair of seats pivotally engaged to the frame and arranged to be swung so as to project toward or away from one another, and a pair of foot rests pivotally carried by the frame below the respective seats and arranged to be swung to reversed positions for co-operation with the seats at the different positions thereof, the foot rests being arranged to meet each other when they are swung to coöperate with the seats when the seats project away from one another.

8. In a device of the character described, a frame comprising side members and a cross member connecting them, a seat pivotally mounted upon the cross member and adapted to be swung to reversed positions, a back coöperable with the seat at its reversed positions, and links connecting the back and said cross member to support the back in its reversed positions.

9. In a device of the character described, a seat, a back coöperable therewith and adapted to be swung to different positions, an oscillatory arm, a link connecting the free end of the said arm and the back, and means for holding the said arm in an upright position.

10. In a device of the character described, a frame having a cross member, a seat pivotally mounted upon the cross member to be swung to reversed positions, a back coöperable with the seat at its reversed positions, oscillatory arms carried by the cross mem-

4
ber, links connecting the arms and back, and means for holding the said arms at a fixed position.

11. In a device of the character described, 5 a frame, a reversible seat carried by the frame, and a reversible foot rest carried by the frame below the seat and adapted to be moved into coöperative relation with the seat at either position thereof.

10 12. In a device of the character described, a frame, a reversible seat carried thereby, and an angular foot rest pivoted adjacent its elbow to the frame, and adapted to be swung to reversed positions for coöperation with 15 the seat at either position thereof.

13. In a device of the character described, a frame, a pair of seats each pivotally engaged with the frame adjacent one edge, whereby the seats may be swung to reversed 20 positions, a back for each seat, means for

supporting the backs at reversed positions for coöperation with those edges of the seats remote from the pivotal points thereof when the seats are in either position, and an angular foot rest pivotally carried by the frame 25 below each seat and arranged to be swung to reversed positions for coöperation with the corresponding seat at either position thereof, the seats, backs and foot rests being adjustable to accommodate the occupants 30 when seated face to face, back to back or facing in the same direction.

In testimony that I claim the foregoing as my own, I have hereto affixed my signature in the presence of two witnesses.

CARL J. JACOBSEN.
